No. 691,478.

Patented Jan. 21, 1902.

J. F. McCANNA.
LUBRICATING PUMP.

(Application filed May 26, 1900.)

(No Model.)

UNITED STATES PATENT OFFICE.

JOHN F. McCANNA, OF CHICAGO, ILLINOIS, ASSIGNOR TO THE JOHN F. McCANNA COMPANY, OF CHICAGO, ILLINOIS, A CORPORATION OF ILLINOIS.

LUBRICATING-PUMP

SPECIFICATION forming part of Letters Patent No. 691,478, dated January 21, 1902.

Original application filed January 6, 1900, Serial No. 545. Divided and this application filed May 26, 1900. Serial No. 18,054. (No model.)

To all whom it may concern:

Be it known that I, JOHN F. McCANNA, a resident of Chicago, in the county of Cook and State of Illinois, have invented certain new and useful Improvements in Lubricating-Pumps, of which the following is a specification.

My invention relates to an improved lubricating-pump employed for forcing oil against pressure into the cylinder of a steam-engine or any other machinery to be lubricated, and relates strictly to the construction of the pump, being a division of my application Serial No. 545, filed January 6, 1900, for improvements in lubricating-pumps for locomotive-engines.

While the present invention was designed, primarily, to be employed in connection with the cup and system whereby I arrange to lubricate locomotive-engines, it will be understood that the pump with which the present application is concerned can be utilized upon a stationary engine or elsewhere.

Referring now to the accompanying sheet of drawings, in which the same reference characters are used to designate identical parts in all the views, Figure 1 is a plan view of the pump. Fig. 2 is a central sectional view on the line A A' of Fig. 1. Figs. 3 and 4 are sectional views on the lines B B' of Fig. 1 and C C' of Fig. 2, respectively; and Fig. 5 is a detail in section on the line D D' of Fig. 3.

For the purpose of applying my invention to locomotive-engines, in which the reservoir must necessarily be in the cab, where it is visible and accessible to the engineer and in which the pumps are preferably near the point at which the oil or lubricant is to be applied, I separate the reservoir from the pumps, mounting the reservoir in the cab, where it is accessible to the engineer, and the pumps in some convenient position adjacent to the air-brake steam-cylinder and the steam-chests of the cylinders for the driving-wheels and any other parts that may be desired to be lubricated.

The framework 6 of the pump is of a generally rectangular box-like construction, and the various sides thereof are preferably

formed integral with each other, except that the end 7 and the top 8 are preferably formed of a piece of sheet metal, making a cover that is hinged to the main casing at 9 and which is conveniently secured in place by the setscrew 10, passing through the aperture in the top part 8 and into a lug 11, formed on the barrel 12 of the pump. A block 13 extends from one side of the casing to the other and has a channel 14 passing therethrough, one end of which is closed by the screw-threaded block 15, while the other end has the screw-threaded end 16 of the supply-pipe, which end is connected to the main portion of the pipe by the elbow 17. It will be apparent that this construction enables me to make connections with the supply-pipe on either side of the pump, as may be necessary in placing them on different sides of the engine.

The barrel 12 of the pump is a piece of some peculiar shape, as will be seen by reference to the drawings. A recess 18, formed in its lower side, communicates with the passage 19, centrally located and leading up from the channel 14, and the valve 20, preferably of the ordinary ball construction, operates as a check-valve. A pair of apertures 21 lead from the recess 18 to the channel 22, which has the plunger or piston 23 of the pump reciprocating therein. An aperture 24 leads from the channel 22 into a recess 25, formed in the piece 26, which is secured to the other parts by the means to be described. A pair of apertures 27 lead from the recess 25 into the channel 28, into the upper end of which is secured the screw-threaded lower end of the discharge-pipe. A check-valve 29, placed in the recess 25, co-operates with the aperture 24. It will be apparent from the description that as the piston 23 is reciprocated the oil will be drawn from the reservoir through the feed-pipe and forced into the delivery-pipe, whence it is delivered into the steam-chest or other part to be lubricated. The pieces 12 and 26 are provided with the arms 30 and 31, respectively, which are apertured for the passage of the bolts 32, which are screwed into the block 13, as shown in Fig. 3, and the nuts 33 upon the upper ends of the bolts 32 when

tightened serve to secure all these members closely together to form the pump. The stuffing-box in the end of the piece 12 is formed in the customary manner with the packing 34, the nut 36, and the gland 35. For reciprocating this piston 23 at the desired rate of speed I provide the shaft 37, which is mounted in the bearings 38, formed in the abutments 39, extending from the sides and end of the casing 6. This shaft is preferably reduced eccentrically, as at 40, and has co-operating therewith the pieces or bearing-blocks 41, which are held together by the elongated rectangular aperture in the yoke 42, which is pivoted on the rod or shaft 43, passing through the casing, at the lower side thereof. For convenience of assembling the parts the yoke 42 is preferably constructed so that one side thereof is formed by the detachable piece 42^a, which is secured to the body of the yoke by the screws 44. The outer screw-threaded end of the piston 23 passes through the aperture 45, formed in the upper end of the yoke, and the lug or nut 46 secured on the piston on the inner side of the yoke, and a nut 47 and a lock-nut 48 serve to form the necessary adjustable abutments by which the length of the throw of the piston can be accurately regulated, as it will be apparent that the closer the nut 47 is brought to the abutment 46 the greater the portion of the swing of the yoke 42 that will be utilized, and consequently the greater the rate of feed. By setting the nut 47 sufficiently far away the pump can be thrown completely out of action, if desired. The shaft 37 is provided with the clutch mechanism 49, which may be of any desired form, but which is preferably like that shown in connection with my Patent No. 648,628, dated May 1, 1900, and by means of this clutch mechanism 49 the vibration of the arm 50, which is preferably secured integral with a disk 51, which is rotatably mounted on the reduced outer end 52 of the shaft 37, will be transmitted to said shaft—*i. e.*, as the arm 50 is vibrated this movement in one direction will be imparted to the shaft 37, so as to give it an intermittent rotary movement in that direction. The swinging movement of the arm 50 may be secured by attaching it in any of the customary mechanisms to any reciprocating part of the engine.

While I have shown my invention as embodied in the form which I at present consider best adapted to carry out its purposes, it will be understood that it is capable of modifications and that I do not desire to be limited in the interpretation of the following claims,

except as may be necessitated by the state of the art.

60

What I claim as new, and desire to secure by Letters Patent of the United States, is—

1. In a device of the class described, the combination with the supply-pipe, of the discharge-pipe, pump connections between said pipes comprising the channel 14 with either end of which the supply-pipe is adapted to be connected, a piston-barrel and a piston therein and means for reciprocating said piston, passages leading from said channel 14 to the discharge-pipe through said piston-barrel, and valves located in said passages on either side of the piston-barrel, substantially as and for the purpose described.

2. In a device of the class described, the combination of the casing having the block 13 therein having the channel 14 extending therethrough, and the passage 19 leading from said channel to the edge of the block, with the piece 12 having the valve-aperture 18 therein and the piston-barrel 22, and the ears 30, and the member 26 connected to the discharge-pipe and having the valve-aperture 25 therein, the ears 31 thereon, and the bolts 32 and the nuts 33 adapted to rigidly connect said members, substantially as and for the purpose described.

3. In a device of the class described, the combination of the shaft 37 and means for rotating the same, with the yoke pivotally mounted adjacent thereto, and having the rectangular aperture therein through which said shaft passes, the blocks 41 surrounding an eccentric portion of said shaft and confined in said aperture, and the piston connected to said yoke, substantially as and for the purpose described.

4. In a device of the class described, the combination of the shaft 37 and means for rotating the same, with the yoke pivotally mounted adjacent thereto, and having the rectangular aperture therein through which said shaft passes, the blocks 41 surrounding an eccentric portion of said shaft and confined in said aperture, and the piston connected to said yoke, the connections between said piston and said yoke comprising the screw-threaded end of the piston having the nuts thereon to form adjustable abutments for said yoke, substantially as and for the purpose described.

JOHN F. McCANNA.
